UNITED STATES PATENT OFFICE.

EDWARD B. TENNEY, OF CLAREMONT, NEW HAMPSHIRE.

DESIGN FOR BEDSPREAD.

Application filed May 16, 1925. Serial No. 13,463. Term of patent 3½ years.

To all whom it may concern:

Be it known that I, EDWARD B. TENNEY, a citizen of the United States, residing at Claremont, in the county of Sullivan and State of New Hampshire, have invented a new, original, and ornamental Design for Bedspreads, of which the following is a specification, reference being had to the accompanying drawing, forming part thereof.

The figure shows a quarter of the bedspread showing my new design which is multiplied symmetrically in the remaining three quarters of the spread, the border shown to be continuous around the center.

I claim:

The ornamental design for bedspread as shown and described.

EDWARD B. TENNEY.
